(57) **CLAIM**

The ornamental design for a toothbrush and/or razor holder, as shown and described.

DESCRIPTION

FIG. 1 is a front side perspective view of an embodiment of a device of the instant invention. The broken lines representing a button form no part of the claimed design.

FIG. 2 is a top plan view of the device of FIG. 1. The broken lines representing a button form no part of the claimed design. FIG. 3 is a front elevation view of the device of FIG. 1. The broken lines representing a button form no part of the claimed design.

FIG. 4 is a bottom view of the device of FIG. 1. The broken lines representing a battery compartment cover form no part of the claimed design.

FIG. 5 is a right side elevation view of the device of FIG. 1. FIG. 6 is a left side elevation view of the device of FIG. 1. FIG. 7 is a rear side elevation view of the device of FIG. 1; and,

FIG. 8 is a rear perspective view of the device of FIG. 1. Various figures include additional broken lines. These additional broken lines are phantom lines that represent points of tangency.
